UNITED STATES PATENT OFFICE.

ARTHUR B. ROBINSON, OF DICKINSON, NORTH DAKOTA.

PHONOGRAPH APPARATUS.

SPECIFICATION forming part of Letters Patent No. 691,000, dated January 14, 1902.

Application filed January 14, 1901. Serial No. 43,200. (No model.)

To all whom it may concern:

Be it known that I, ARTHUR B. ROBINSON, a citizen of the United States, residing at Dickinson, in the county of Stark, State of 5 North Dakota, have invented certain new and useful Improvements in Phonograph Apparatus, of which the following is a specification.

The invention relates particularly to coin-controlled multiple-record apparatus, which 10 may be of the general character shown in my Patent No. 634,025, dated October 3, 1899, or of other types to which this invention is applicable either in the special form herein disclosed or in other forms capable of producing 15 like results and which may no doubt be readily devised by those skilled in such matters without departing from the principles of my invention. The general purpose of the invention is to prevent the movement of the 20 reproducer into working position until a record has been properly placed in coöperative relation to it and to prevent the record while the reproducer is in action from being moved or shifted.

25 In the accompanying drawings I have indicated an apparatus like or the same as that disclosed in my patent above mentioned.

Figure 1 is a vertical section on the line 11 of Fig. 2; Fig. 2, a plan view of one side of 30 the machine with one of the side plates or standards of the frame in section, and Fig. 3 a detail sectional view on the line 3 3 of Fig. 2; Fig. 4, a detail plan view showing the reproducer and its actuating and controlling 35 mechanism; Fig. 5, an elevation of the left-hand end thereof; Fig. 6, an elevation of right-hand end; Fig. 7, a detail elevation, partly broken away, indicating the reproducer and some associated parts; and Fig. 8, a 40 detail section in the line 8 8 of Fig. 4.

A is the disk carrying the multiple records B, and C its shaft, to which the spring D is applied, the organization being such that the shaft may be drawn outwardly and it and the 45 disk rotated to bring either of the records into coöperative relation to the reproducer, all as fully disclosed in my patent.

E is the ordinary rising-and-falling or rocking reproducer, and F the ordinary rocking 50 "shipping-trough," controlling the up-and-down position of the reproducer.

In apparatus of this kind there is danger

of the reproducer being thrown forward at a time when a record is not in position to receive it, a condition liable to result, by reason 55 of the subsequent rotation of the reel or group of records, in injury to both the reproducer and one or both of two adjoining records. There is also liability of injury both to the reproducer and records should the shaft be 60 manipulated in an attempt to turn up a new or adjoining record while the reproducer is in operative contact with another one. Broadly speaking, the invention consists in means for preventing the occurrence of either of these 65 conditions. Such means or mechanism may of course be embodied in various forms. That which experience has demonstrated to be a suitable, practical, and efficient one is shown in the drawings and is as follows: 70 Coupled to the ordinary shipping-trough, which rises as the reproducer descends, and vice versa, by a pin-and-slot connection G, is a lever H, pivoted in rear of such connection, as in a bracket I, and whose rear end h extends over the shaft C. In the shaft is an 75 annular groove c, with which the end of the lever engages. When the shaft C is in its normal position, the lever enters the slot as the reproducer moves into operative relation 80 to a record B and locks the shaft against endwise movement. Should the shaft not be in normal position when the reproducer is moved forward, the end of the lever abuts against an ungrooved part of the shaft and arrests 85 the forward movement of the reproducer. In the construction shown the bearing-box K of the shaft is slotted at k, and the end of the lever is guided in the slot. When the shaft is in normal position, the annular groove 90 therein is opposite the slot. A usual construction of apparatus of this general character is shown in Figs. 4 to 8.

L is the winding-shaft, on which is secured the gear l, which meshes with the gear l' of the 95 usual spring or weight motor.

M is the coin-chute, and M' M² M³ the levers or latches associated therewith and with the ratchet-wheel N and which permit the operation of the winding-shaft.

100 The reproducer support or carriage E' is mounted on the sleeve E³ and guided below by the part E⁴ on the shaft E². The sleeve E³ slides on the longitudinally-slotted sleeve

O, which incloses the usual screw feed-shaft P. The lower part E⁴ of the reproducer carriage or support is of hollow construction and contains the feed-block e, which is engaged by the spring e' and actuated by the cam-piece e³. This mechanism is of usual construction and is clearly shown in cross-section in Fig. 8.

Mounted on a stud-bearing on the right-hand upright of the machine is the toothed wheel Q, which is so located that a pin l² on the winding-shaft can engage with its teeth. On the wheel Q are two pins q and q', which engage with the latch R and with a lug f' on the end f of the shipping-trough F. This trough is normally drawn down by the spring f² and held by a latch R, controlled by the spring r. The trough F is pivoted to the end frame by screw f³. In the trough is a spring S, which returns the reproducer and its connected parts to their normal position at the left-hand side of the machine after a composition has been rendered.

At the left-hand side of the machine are located the above-mentioned latches or levers M' M² M³ and the ratchet-wheel N. The lever M' is pivoted at m and has a pawl end m', adapted to engage the ratchet-wheel N, and having a pin m², that is partially encircled by a lug m³ on the upper portion of the lever M², pivoted at m⁴. Also pivoted at m⁴ is the lever M³, which has a projecting lug m⁵, adapted to work against the edge of the free end of the part M².

The operation is as follows: When a coin is deposited in the coin-slot M, it depresses the lever M' and disengages its pawl end m' from the ratchet-wheel N. The coin, however, is not allowed to drop past the lever M', as the pin m² on the lever is prevented from continuing its upward movement by the lug m³ on the latch M². The winding-shaft can now be revolved in the direction indicated by the arrows in Figs. 5 and 6. The wheel Q is revolved by the pin l² on the winding-shaft engaging with its teeth until the pin q, mounted thereon, engages the lug f' and raises the trough F, that carries with it the cam-piece e³, which permits the feed-block E⁴ to engage the screw feed-shaft P, and also permits the reproducer-carriage to drop the reproducer upon the record. The screw feed-shaft P engaging the feed-block causes the reproducer to feed across the record against the tension of the spring S. During the reproduction of the record the winding-shaft revolves in an opposite direction to that shown by the arrow and carries around tooth by tooth wheel Q in a direction opposite to that indicated by the arrow thereon. On the first revolution of the winding-shaft now occurring the pin n' on the ratchet-wheel N will contact with the lever

M³ and move it until the lug m⁵ has carried the latch M² to such position that its lug m³ has passed out of the way of the pin m², thus permitting the coin to carry the lever M' down and fall into a receiving-box, (not shown,) when the lever M' will return to its normal position. The winding-shaft continues to revolve until the pin q' on the wheel Q contacts with and disengages the latch R from the trough end f, at which time the spring f² will return the trough to its normal position. The trough F will carry with it the cam-piece e³, which first raises the reproducer and then disengages the feed-block from the screw-shaft. The spring S now pulls the reproducer and its associated parts to their normal position at the left of the machine. An adjustable stop and buffer O' is provided to lessen the blow of impact.

I claim as my invention—

1. In a multiple-record phonograph apparatus, the combination with the multiple-record carrier, reproducer and screw feed-shaft with which the reproducer is engaged when lowered and disengaged from when raised, of a locking mechanism operated by the raising of the reproducer to lock the multiple carrier when in a normal position against manipulation.

2. In a multiple-record phonograph apparatus, the combination with the multiple-record carrier, reproducer and screw feed-shaft with which the reproducer is engaged when lowered and disengaged from when raised, of a locking mechanism controlled by the up-and-down movement of the reproducer, and acting either to prevent the descent of the reproducer if the carrier is not in a normal position, or on the descent of the reproducer to lock the carrier if it is in a normal position.

3. In a multiple-record phonograph apparatus, the combination of the multiple-record carrier having an endwise-movable annularly-grooved shaft, the rocking reproducer, the screw feed-shaft with which it is engaged when lowered and from which it is disengaged when raised, the rocking trough controlling the position of the reproducer, and a locking-lever actuated by the trough to either enter the groove and lock the carrier if in a normal position when the reproducer descends, or to abut against the shaft and prevent the descent of the reproducer if the carrier is not in a normal position.

In testimony whereof I have hereunto subscribed my name.

ARTHUR B. ROBINSON.
